FIG. 3.

UNITED STATES PATENT OFFICE

2,352,092

STOKER APPARATUS

Robert A. Foresman, Prospect Park, Pa., assignor to Westinghouse Electric & Manufacturing Company, East Pittsburgh, Pa., a corporation of Pennsylvania

Application February 6, 1943, Serial No. 474,915

6 Claims. (Cl. 74—586)

This invention relates to fuel-feeding means for stokers, more particularly to secondary rams for stokers of the underfeed type, and has for an object to provide improved and novel stroke-adjusting mechanism for such secondary rams.

Another object of the invention is to provide secondary ram stroke-adjusting mechanism capable of infinite adjustments between zero stroke and maximum stroke.

These and other objects are effected by the invention as will be apparent from the following description and claims taken in connection with the accompanying drawings, forming a part of this application, in which:

Fig. 1 is a fragmentary sectional view of a secondary ram and the driving means therefor, together with stroke-adjusting mechanism embodying the present invention;

Fig. 2 is a transverse sectional view taken along the line II—II of Fig. 3, looking in the direction indicated by the arrows, but with the crosshead shown in elevation; and,

Fig. 3 is a longitudinal sectional view taken through the stroke-adjusting mechanism of Fig. 1.

Referring now to the drawings more in detail, there is shown a stoker 10 inclined downwardly and rearwardly from the furnace front wall 11 and comprising a plurality of spaced-apart rows of tuyères 12, providing therebetween spaced retorts 13, each adapted to have fuel fed thereto from the hopper 14 through the ram box 15 by reciprocation of the ram 16. Reciprocatory motion is imparted to the ram through the gear box 18, receiving power from any suitable source (not shown) and operating through the eccentric 19 and the connecting rod 20.

A conventional secondary ram structure 22 positioned within the retort 13 provides for movement of fuel rearwardly therealong, the secondary ram having reciprocatory motion imparted thereto by the driving rod 23 positioned below the bottom of the retort. A pair of driving links 24 provides for transmission of motion from the connecting rod 20 to the driving rod 23 through the novel stroke-adjusting mechanism 25 comprising the present invention.

Referring now to Figs. 2 and 3, there are shown a pair of spaced parallel housing members 27 and 28 having bosses 29 on their upper surfaces and adapted to be secured by bolts 30 and nuts 31 to conventional structural members 32 extending longitudinally beneath the retort and serving also to support the ram box 15. Spacing bars 33 are clamped between the bosses 29 and the

structural members 32 and serve to brace the structure.

The spaced housing members 27 and 28 have grooves 36 formed in their opposed faces for the reception of guide members 37 slidable longitudinally therein. Each guide member 37 is provided with a circular recess 38 for reception of the cylindrical trunnions 39 of the crosshead 40, with the result that the crosshead is supported 10 for pivotal movement about the longitudinal axes of the trunnions 39 and for bodily sliding movement longitudinally of the grooves 36 in the housing members 27 and 28.

The driving links 24 are provided at their rearward ends with circular openings 42 adapted to receive the trunnions 39 of the crosshead with the driving links positioned between the crosshead proper and the guide members 37. It will be apparent that this arrangement provides for reciprocation of the crosshead 40 upon reception of the connecting rod 20 and the associated driving links 24. The forward ends of the driving links are provided with elongated slots 43 slidably receiving a headed pin 44 carried by the 20 depending arm 45 of the connecting rod 20, the elongated slot and pin providing a lost motion connection providing for lesser travel of the driving links 24 than of the connecting rod 20.

The crosshead 40 is provided with a centrally-located cylindrical bore 47 adapted to slidably receive an externally-threaded portion 48 at the forward or upper end of the driving rod 23.

It will be apparent that the construction described above provides a self-aligning structure 35 resulting in free sliding action of the crosshead with respect to the driving rod 23, regardless of minor misalignments of the housing members and associated parts.

Sliding movement of the crosshead with respect to the threaded portion of the driving rod is limited in an upward or forward direction by a split key collar 49 provided with a radial, inwardly-extending flange 50 adapted to be positioned within a circumferential groove 51 formed adjacent the end of the driving rod, the retaining collar 52 embracing the segments of the split key collar 49 and retaining them in assembled relation with respect to the end of the driving rod 23.

Sliding movement of the crosshead 40 with respect to the rod 23 in a rearward direction is limited by the nut 55, threadedly mounted on the threaded portion 48 of the driving rod and movable therealong when rotated with respect thereto.

The threaded portion 48 of the driving rod 23 is of such length that with the nut 55 moved rearwardly as far as possible, the latter will be out of engagement with the crosshead throughout reciprocation of the latter. It will be apparent that, by moving the nut 55 forwardly, for example, to the position illustrated in Fig. 3, the crosshead 40 will engage the nut during its rearward movement and acting through the nut will impart rearward motion to the driving rod 23. During the return stroke of the crosshead it will first slide upon the threaded portion of the driving rod until it engages the split key collar 49, whereupon during the remainder of its return stroke it will move the driving rod forwardly. If the nut 55 is adjusted toward the forward end of the threaded portion of the driving rod so that the crosshead 40 engages both the split key collar 49 and the nut 55 simultaneously, the entire motion of the crosshead will be imparted to the driving rod to give maximum movement to the secondary ram structure. Thus it will be apparent that the motion of the secondary ram may be given an infinite number of adjustments ranging from zero to maximum stroke.

To provide for convenient adjustment of the nut from a point that is readily accessible, there is formed about the periphery of the nut 55 a row of teeth 56, forming, in effect, a gear. A driving gear 57 and an idler gear 58 are mounted in a gear casing 59 which also encloses the gear teeth 56 formed on the nut, the idler gear 58 meshing with the driving gear 57 and the teeth 56 on the nut, with the result that rotation of the driving gear results in corresponding rotation of the nut.

In order to prevent rotation of the gear casing and its enclosed train with respect to the threaded portion of the driving rod 23, while at the same time permitting longitudinal travel of the casing and train, there is provided a shaft 61 which is square in cross section and is slidably received through a square opening 62 extending through the driving gear 57, axially thereof. The shaft 61 is provided with trunnions 63 and 64 rotatably mounted in bearings 65 formed in spacer plates 66 secured to opposite ends of the housing members 27 and 28 by bolts 67. It will be noted that the spacer plates 66 are provided with a second set of bearings 68 concentrically opposed to the bearings 65, with respect to the vertical centerline of the mechanism, whereby, if desired, the square shaft 61 may be mounted at the other side of the vertical centerline.

The forward end of the square shaft 61 is connected, through a universal joint 69, with an operating rod 70 extending forwardly and terminating with suitable manual means, such as the handwheel 71, located at a point readily accessible to an operator during operation of the stoker.

While the invention has been shown in but one form, it will be obvious to those skilled in the art that it is not so limited, but is susceptible of various changes and modifications without departing from the spirit thereof, and it is desired, therefore, that only such limitations shall be placed thereon as are specifically set forth in the appended claims.

What is claimed is:

1. Stoker mechanism comprising a ram-operating member including an externally threaded portion adjacent one end; a nut in threaded engagement with said threaded portion and providing an abutment; means providing spaced par-

allel guides at opposite sides of the threaded portion; a crosshead closely surrounding said threaded portion and slidably longitudinally thereon into and out of engagement with the abutment on said nut; guide blocks supporting said crosshead and being slidably supported by the spaced parallel guides; means providing a stop on the ram-operating member at the side of the crosshead opposite to the nut, whereby movement of said crosshead along said operating member is limited in one direction by said stop and in the other direction by the nut; means for imparting reciprocatory motion to said crosshead; and means whereby the nut may be rotated on the threaded portion to vary its position longitudinally of the ram-operating member.

2. Stoker mechanism comprising a ram-operating member having a threaded portion; a nut on said portion and providing an abutment; spaced parallel guides at opposite sides of the threaded portion; guide blocks slidably supported by said guides; a crosshead supported by said guide blocks and having an opening therethrough slidably receiving the threaded portion; a stop member carried by the ram-operating member at the side of crosshead opposite the nut, whereby movement of the crosshead along said operating member is limited in one direction by said stop and in the opposite direction by said nut; means whereby reciprocatory motion may be imparted to said crosshead; and means for rotating the nut on the threaded portion to vary its position longitudinally of the ram-operating member.

3. Structure as specified in claim 2, wherein the means for rotating the nut comprises teeth formed about the periphery of the nut, a housing enclosing the toothed portion of said nut, a train of meshing gears within said housing with the last gear of said train meshing with the teeth of said nut, and means for rotating the first gear of the train and for preventing rotation of the housing.

4. Stoker mechanism comprising a ram-operating member having a threaded portion; a nut on said portion providing a first abutment; a stop on the member providing a second abutment spaced from the first abutment longitudinally of the member; a crosshead slidably mounted on the ram-operating member between said first and second abutments and adapted, when moved in one direction, to engage the first abutment and impart motion to the ram-operating member and, when moved in the opposite direction, to engage the second abutment and impart motion to the ram-operating member in said opposite direction; means providing spaced parallel guideways at opposite sides of the ram-operating member; guide members slidably supported in said guideways and supporting the crosshead; means for imparting reciprocatory motion to said crosshead; and means for selectively varying the position of the first abutment longitudinally of the ram-operating member, said means comprising gear teeth formed about the periphery of said first abutment, gear means by which said abutment may be rotated relative to the threaded portion of the ram-operating member, and means for operating said gear means.

5. Structure as specified in claim 4, wherein the first abutment may be moved along the threaded portion of the ram-operating member a distance equal to the travel of the crosshead, whereby the travel of said ram-operating mem-

ber may be selectively varied from zero to an amount equal to the travel of the crosshead.

6. Stoker mechanism comprising a ram-operating member; a pair of abutments carried by and spaced longitudinally of said member; a crosshead slideable along the ram-operating member between said abutments and adapted, when moved in one direction, to engage one of the abutments and impart motion to the ram-operating member and, when moved in the opposite direction, to engage the other abutment and impart motion to the ram-operating member in said

opposite direction; means providing spaced parallel guideways at opposite sides of the crosshead; guide members slidably supported in said guideways and supporting the crosshead; means through which reciprocatory motion may be imparted to said crosshead; and screw means for selectively varying the position of one of the abutments longitudinally of the ram-operating member, whereby the amount of movement imparted to said ram-operating member by the crosshead may be selectively varied.

ROBERT A. FORESMAN.
